(57) **CLAIM**

The ornamental design for a nesting buckle, as shown and described.

DESCRIPTION

FIG. 1 is a perspective view of my design for a nesting buckle;

FIG. 2 is an exploded perspective view of the nesting buckle;

FIG. 3 is a top view of a first component of the nesting buckle, the bottom view being a mirror image thereof;

FIG. 4 is a front view of a first component of the nesting buckle;

FIG. 5 is a rear view of a first component of the nesting buckle;

FIG. 6 is a left side view of a first component of the nesting buckle, the right side being a mirror image thereof;

FIG. 7 is a top view of a second component of the nesting buckle, the bottom view being a mirror image thereof;

FIG. 8 is a front view of a second component of the nesting buckle;

FIG. 9 is a rear view of a second component of the nesting buckle;

FIG. 10 is a left side view of a second component of the nesting buckle, the right side view being a mirror image thereof;

FIG. 11 is an exploded top view of a first and second component of the nesting buckle, the bottom view being a mirror image thereof;

FIG. 12 is a top view of a first and second component of the nesting buckle;

FIG. 13 is a front view of a first and second component of the nesting buckle;

FIG. 14 is a rear view of a first and second component of the nesting buckle;

FIG. 15 is a left side view of a first and second component of the nesting buckle, the right side being a mirror image thereof; and,

FIG. 16 is a bottom view of a first and second component of the nesting buckle.

The broken line showing of webbing in the figures depicts environmental subject matter that forms no part of the claimed design.

1 Claim, 3 Drawing Sheets
